JET-TYPE PROPULSION EQUIPMENT FOR BOATS

William H. Gruber, Kansas City, Mo.

Application May 28, 1954, Serial No. 433,109

5 Claims. (Cl. 122—47)

This invention relates to self-propulsion equipment for boats and particularly to the generation and novel use of steam under pressure as the motive power for boats.

The most important object of the present invention is the provision of an underwater, directional nozzle through which steam under pressure jets to drive a boat by the reaction of the steam jet to a body of water carrying the boat.

A further important object of the present invention is to provide a waterflow tube into which the nozzle discharges, the flow of water through the tube responsive to the steam jet being also the primary means of steering the boat.

Another object of the present invention is the provision of a steam generator including a water drum and a source of combustion within a fireproof compartment, the walls of the latter being associated with the boat as integral, structural elements thereof.

With these and other objects in view, the propulsion equipment for boats of the present invention generally comprises a steam generator which is mounted within a boat; a rotatable steering column through which steam under pressure travels to a directional nozzle on the lowermost end of the steering column; and various steam control means associated with the equipment, including a safety valve, a throttle valve and a feedwater pump for maintaining the water level within the water drum.

Other objectives include the provision of a rudder section on the steering column; an auxiliary feed line leading from the pump to the water drum; and many, more minor objects which will become apparent in the following specification and from a study of the appended drawings, wherein:

Figure 1 is a fragmentary, side, elevational view of a boat having the propulsion equipment of the present invention associated therewith, parts being broken away and in section to reveal details of construction.

Fig. 2 is a fragmentary, rear elevational view of the boat and propulsion equipment shown in Fig. 1.

Fig. 3 is a fragmentary, transverse, cross-sectional view taken on line III—III of Fig. 4, parts being broken away for clarity.

Fig. 4 is a longitudinal, cross-sectional view taken on line IV—IV of Fig. 3.

Fig. 5 is an enlarged, fragmentary, longitudinal cross-sectional view taken on line V—V of Fig. 2; and

Fig. 6 is a fragmentary, top view as indicated by the line VI—VI of Fig. 2.

Referring now to the drawings, the boat with which the jet-type propulsion equipment of the present invention is adapted for use is designated broadly by the numeral 10, the stern section only of the boat 10 being illustrated in the drawings. Viewing Figs. 1, 3 and 4, it is noted that a fireproof compartment 12 is bounded on all sides by fire walls 14, all of which are integrally attached to the boat 10, as structural elements thereof.

A steam generator designated broadly by the numeral

2

16 (Fig. 3) is situated within compartment 12 and consists generally of a U-shaped water drum 18, a U-shaped fire tube 20 within drum 18 and a fire box 22, the latter being integrally attached to adjoining fire walls 14. The upper leg of drum 18 is mounted on upper fire wall 14 by means of U-shaped hangers 24, while the lower leg of drum 18 fits within fire box 22, as shown in Fig. 3. Thus the drum 18 and the fire tube 20 may be removed and replaced upon disassembly of one of the fire walls 14.

10 A source of combustible material (not shown) supplies burners 26 which extend into the compartment 12 from a manifold 28. Viewing Figs. 3 and 4, it is seen that the center burner 26 extends into fire tube 20 whereas the outer burners 26 extend into compartment 12. The upper and lower legs of drum 18 are interconnected by opposed rows of arcuate cross-connectors 30 which enhance the natural circulation of water within drum 18. An opening 32 in fire box 22 is normally closed by a fire-proof door (not shown), which renders the fire box 22 accessible for lighting off burners 26. The rear fire wall 14 is provided with conventional exhaust outlets 31 which communicate with compartment 12 and which have baffles 33 therein.

In the construction of drum 18, it is to be noted that the legs thereof are spaced, and that drum 18 is free for uniform expansion or contraction in any direction, without imparting stresses to any particular section of the drum 18.

30 For the reasons detailed in the last paragraph, the U-shaped configuration of drum 18 and fire tube 20 are of primary importance in the disclosure of the present invention. Manifestly, when such adaptations become fully practicable, the equipment of the present invention will be of the utmost importance and utility in boats and waterborne craft having other design characteristics than the boat 10 chosen for illustration.

35 Steam which is generated within drum 18 escapes therefrom through a riser 34, the latter being coupled with a lateral conduit 36 by means of a union joint 38.

Joint 38 threadably receives safety apparatus designated broadly by the numeral 40 and including a pressure gauge 42, a safety valve 43 having a stem 44, and a laterally extending blow-off pipe 46. A throttle valve 48 having a handle 50 and a closure cap 52 also forms a part of lateral conduit 36.

40 A hollow, steering column 54 depends from conduit 36 and is rotatably mounted thereon by means of a joint 56. A spindle 58 rotates with column 54, relative to joint 56, and is adapted to receive steering apparatus (not shown). Manifestly, the normal path of travel of steam generated within drum 18 is upwardly through riser 34, through conduit 36 and into hollow column 54.

45 There is provided at the lowermost end of column 54 a restricted neck portion 60, the latter being closed by a laterally extending nozzle 62. It is to be noted that steam discharging from nozzle 62 enters an elongated tube 64 through which water freely flows as steam jets from nozzle 62. The tube 64 is rigidly mounted on neck portion 60, substantially perpendicular thereto, and has an opening 65 which receives the nozzle 62. The tube 64 has a restricted diameter at the outlet end thereof, as clearly shown in Fig. 5. A rudder 66 circumscribes the neck portion 60 and terminates in a pair of fins 68 which are parallel with tube 64 and nozzle 62.

50 Referring now to Figs. 2, 3 and 6, the embodiment of the present invention chosen for illustration includes, as an element thereof, a feedwater pump 70 having a suction line 72 which terminates below the water line of boat 10 exteriorly thereof. The outlet of pump 70 is directed to the drum 18 by either of two paths of travel, depending on the water level therein, as indicated in a

gauge glass 74 having arms 76 and 78 communicating with drum 18. When the water level in drum 18 is low, a valve 80 in feed line 82 may be opened to permit rapid filling of drum 18. When the water level in drum 18 is normal, the valve 80 may be closed and feedwater from pump 70 will enter drum 18 only through feed service line 84 which terminates within drum 18 in a spray tip 86. Manifestly, the pump 70 is driven by steam under pressure which enters through a steam line 88, the latter being coupled to riser 34 by means of a valve 90. A check valve 92 is provided in feed line 82, in the event an excessive back pressure builds up either within drum 18 or pump 70.

In operation, assuming a water level in drum 18, lighting off of the burners 26 serves to build up a pressure within drum 18 and to generate steam therein. At this stage, steam valve 90, feed valve 80 and throttle valve 48 are closed. When a sufficient head has been developed, opening of steam valve 90 and feed valve 80 will drive the pump 70 and deliver feedwater to the drum 18 through feed line 82 until a proper level is indicated in gauge glass 74. At this time, the valves 80 and 90 are closed, the latter being left slightly open so as to deliver only enough steam to pump 70 to maintain feedwater delivery through spray tip 86 of feed service line 84.

Should an excessive pressure head develop within drum 18, before opening of throttle valve 48, such excess will exhaust through blow-off pipe 46 after opening of safety valve 44. When throttle valve 48 is opened, steam under pressure enters column 54 and discharges therefrom through nozzle 62 in the form of a jet stream. The boat 10 is driven through the water in which it has been floated by the reaction of the jet stream discharging from nozzle 62 on such body of water. Manifestly, a high velocity stream of water passes through the tube 64 and serves not only to drive the boat through the water but also as a means of steering the boat 10, since the column 54, nozzle 62 and tube 64 are rotatable as a unit when spindle 58 is actuated by the steering apparatus (not shown).

Should the gauge glass 74 indicate, at the time the propulsion equipment of the present invention is to be placed in operation, that there is an excessively low water level within drum 18, the latter may be filled initially by swinging suction line 72 upwardly, the latter being pivotally mounted in a joint 73 on feed line 82.

It is obvious that the embodiment herein disclosed is a preferred form only and that many changes or modifications may be made therein without departing from the broad principles of the present invention. Such changes or modifications are contemplated hereby and it is, therefore, desired to be limited only by the scope of the appended claims.

Having thus described the invention, what is claimed as new and desired to be secured by Letters Patent is:

1. In propulsion equipment, a housing having fireproof walls; a U-shaped, tubular, water drum having a bight, a first leg and a second leg, said drum being provided with a water inlet and a steam outlet, said legs being closed at the outermost ends thereof; a fire tube within said drum, said tube extending from end to end of the drum and passing through said ends; means mounting said first leg on one of said walls with the second leg disposed therebeneath; and a source of heat energy within the housing and discharging into said tube, said outlet and inlet being in said first leg, said source discharging into said tube adjacent the outermost end of the second leg.
2. In propulsion equipment as set forth in claim 1 wherein is provided a plurality of cross-connector tubes interconnecting said legs and communicating therewith.
3. In propulsion equipment as set forth in claim 2 wherein said source of heat energy includes a fire box mounted within said housing and receiving said second leg of the drum.
4. In propulsion equipment as set forth in claim 3 wherein said means mounting the first leg comprises a plurality of hanger members suspending said first leg from the upper wall of said housing.
5. In propulsion equipment, a fireproof housing having upper, lower and side walls; a U-shaped, tubular, water drum having a bight, a first leg and a second leg, the legs being closed at the outermost ends thereof; means suspending said first leg from said upper wall; a fire tube extending through said drum in substantially coaxial alignment therewith; a fire box mounted on said lower wall and receiving said second leg; and a source of heat energy within the box and discharging into said tube.
